UNITED STATES PATENT OFFICE.

LAFAYETTE HINCKLEY, OF SAN FRANCISCO, CALIFORNIA, FRANCES C TREADWELL, OF SAME PLACE, ADMINISTRATRIX OF SAID HINCKLEY, DECEASED.

METHOD OF HANDLING NITRO-GLYCERINE.

SPECIFICATION forming part of Letters Patent No. 240,516, dated April 26, 1881.

Application filed November 23, 1880. (No model.)

To all whom it may concern:

Be it known that I, LAFAYETTE HINCKLEY, of the city and county of San Francisco, in the State of California, have invented an Improved Method of Rendering Nitro-Glycerine and its Compounds Non-Explosive by Ordinary Shocks or Jars; and I do hereby declare that the following is a full, clear, and exact description thereof.

10 The object of my invention is to render nitro-glycerine, and such highly-explosive compounds as contain nitro-glycerine secure from explosion by accident or percussin, so that they can be safely handled in bulk or fired out of 15 a gun without being exploded by the shock or jar resulting therefrom.

I have discovered that if nitro-glycerine, or any compound containing nitro-glycerine, be confined in a vessel, tube, cartridge, or shell 20 under pressure it cannot be exploded by any ordinary amount of shock, jar, or percussion to which it may be subjected in transportation or handling, and that cartridges or shells loaded with nitro-glycerine or any of its explosive products or combinations can be safely 25 fired out of a gun or cannon without being exploded by the shock, if it be confined in the cartridge or shell under pressure, and that when thus confined no force less than one sufficient to shatter or burst the cartridge or 30 shell will cause it to explode. This enables me to load a shell with nitro-glycerine, giant-powder, or other compound containing nitro-glycerine, and fire it from a gun or cannon 35 with ordinary gunpowder. The shock consequent on firing the shell will not explode the nitro-glycerine contained in the shell; but the concussion or sudden force consequent on the striking of the shell at the end of its flight 40 will, if it strikes a solid substance, shatter or burst the shell, and cause the nitro-glycerine or its compound to explode with fearful violence and effect.

Nitro-glycerine can be put up in cartridges 45 under pressure, and in this condition transported from place to place without the least danger of accidental or spontaneous explosion, and cartridges thus prepared will be the cheapest and most effective blasting agent in

existence, as the nitro-glycerine can be exploded by means of a cap in the usual way. Such cartridges are especially valuable for open-air blasting, or for blasting under water.

Nitro-glycerine, by being kept in vessels under pressure, can be transported in bulk with 55 as much safety as ordinarily-inflammable oils.

In constructing and manufacturing shells of the character above mentioned I make the shell with a screw-plug arranged to screw into its base. The screw-threads in the base of 60 the shell in which the screw-plug enters I coat or fill with soft solder or other impermeable substance. I also coat the shell, either inside or outside, with solder, in order to prevent the nitro-glycerine from being forced through the 65 pores of the iron shell. I then fill the shell with nitro-glycerine, or with a nitro-glycerine compound, and screw the plug into the base-opening until the desired pressure upon the contained explosive is obtained. The screw-threads on the plug will cut their way into the 70 solder without causing an explosion, even if a portion of nitro-glycerine should be ground between them. This fact I have proven by frequent tests. The force which explodes nitro-glycerine must be a sudden force, percussive in its character, and it must act directly 75 upon the nitro-glycerine.

The amount of pressure necessary to be exerted on the glycerine is immaterial, so long 80 as it prevents any quick action of the glycerine when it is subjected to motion, jar, or shock.

Having thus described my invention, what I claim, and desire to secure by Letters Patent, 85 is—

The mode or method of rendering nitro-glycerine and compounds containing nitro-glycerine non-explosive by ordinary shocks or jars, consisting in confining it in closed vessels, 90 tubes, cartridges, or shells under pressure, substantially as above specified.

In witness whereof I have hereunto set my hand and seal.

LAFAYETTE HINCKLEY. [L. S.]
